TREATING SHOE LININGS

Dominick La Valle, New York, N. Y., assignor to
 United Shoe Machinery Corporation, Paterson,
 N. J., a corporation of New Jersey

Application December 24, 1936, Serial No. 117,549

3 Claims. (Cl. 12—146)

This invention relates to a method of treating raw-edged stock, such as is found in shoe linings, and to a shoe construction embodying a lining treated in accordance with this method.

5 Shoes are frequently constructed with leather linings of a contrasting and usually a lighter color than the outside of the shoe. Such linings, frequently of sheepskin, are often sewed to the upper with the exposed cut edge raw or untreated. It 10 has long been realized, however, that such a shoe construction is undesirable because the uncolored raw edge of the lining is so conspicuous both before and after the shoe is on the foot. One attempted solution of the difficulty requires the 15 assembled upper to be passed between compression members thereby to reduce the thickness of the lining. Efforts have even been made to conceal this raw edge, as by curling the upper inwardly to hide the lining. These treatments are 20 expensive and not wholly successful.

An object of the present invention is to provide an improved method of treating raw-edged stock, such as shoe linings, so that the edge will be less conspicuous.

25 The leather which is employed for shoe linings is usually light colored and is soft and flexible and for this reason the fibers are not well consolidated. Consequently, when the lining is trimmed to fit the upper to which it has been stitched, the raw 30 edge frequently is fuzzy and has tiny bunches and streamers which render it all the more conspicuous against the darker background of the adjacent shoe upper. Accordingly, one aspect of the invention resides in the treatment, over an area 35 which does not have to be accurately defined as long as it surely includes the final margin, of such a piece of leather by a material having some adhesive or binding qualities which will consolidate the leather fibers, thereby reducing the apparent 40 thickness of the leather and, in some cases, reducing the actual thickness. Such consolidation increases the density of the leather and makes it easier to trim with a clean cut.

45 It would be desirable to ink the exposed edge of the lining to make its color conform to that of the adjacent upper but, in view of its thinness and the further fact that it is not desired to discolor the exposed inner grain surface of the leather lining, such an inking is impractical except in 50 making the highest grades of shoes where high wages are paid for applying ink to the edges of linings with a very fine brush. However, the invention, in another aspect, resides in the treatment of the inner margin of the leather lining 55 adjacent to the final edge by means of an ink

which will penetrate through a part of the thickness of the lining and thereby change the color of a portion of the exposed edge without discoloring the grain surface.

From another viewpoint, the invention resides in a shoe lining, or in a shoe construction embodying such a lining, in which the exposed raw edge is colored across a portion of its width. This color preferably blends with or matches that of the adjacent upper or of the French binding 10 which may have been applied to the edge of the upper and minimizes the apparent thickness of the exposed edge of the lining. At the same time, the edge portion may be made denser and consolidated and made less noticeable.

15 The invention will be best understood from a consideration of the following specification, taken in connection with the accompanying drawing, in which:

Fig. 1 illustrates the application of a coloring 20 and consolidating material to the inner face of a quarter lining, and

Fig. 2 is a perspective view of a portion of the 25 upper edge of a shoe upper with its attached lining, a portion of which has been treated in accordance with the invention and a portion of which remains untreated.

The manner of application of ink to the margin of the inner surface of the lining is not a part of my invention and I have, accordingly, shown it as 30 carried out by means of any suitable device or tool, such as a brush 10, drawn along the flesh surface of the lining 12 to apply a stripe 14 of an ink which will combine the consolidating and coloring features previously mentioned. The 35 term "ink" is here used in its generic sense to include any dye or other coloring material. A binder or consolidating agent, such as a gum, wax, adhesive, resin or the like may be embodied in the ink compound to aid in securing the desired result. 40

In many factories, it is the practice to cut the lining larger than the quarter so that it extends above the upper edge thereof, to assist in lasting or the like. In that case, the area of the lining which will be treated is a stripe spaced from the 45 actual edge of the lining and which will be wide enough to surely include the line of cut 15 which will form the edge of the lining in the finished shoe. The formation of a raw edge is sometimes done at the time of top stitching, i. e., when forming the seam 26, this being accomplished by a knife on the sewing machine. In other cases, the lining is trimmed by means of a special trimming machine, usually after lasting.

55 A shoe upper, around the margin of the foot

opening, usually comprises a piece of upper leather 16, the upper edge of which may be concealed by means of French binding 18 held there-to by stitching 20 and turned over the edge of the upper, being usually stuck to the flesh surface thereof at 22. The lining is usually attached to the upper by a row of top-stitching 26, leaving its raw edge 24 exposed just inside the French binding 18. If this raw edge is untreated, as indicated at 30, it will be fuzzy and, upon close examination, will be seen to comprise tufts or streamers 32, 34 which are particularly conspicuous where they lie immediately adjacent to the French binding 18.

15 If the lining has been treated as indicated in Fig. 1, then these fibers will be consolidated, reducing the thickness of the lining, as shown at 36, and discoloring a portion of the width or thickness of the exposed edge, as indicated at 38. This 20 discoloration will obviously extend down into the margin of the leather, as at 40, but this does not matter because no attempt is made to treat an exact width of margin and it is convenient to extend the treatment over an area which will 25 be large in comparison with the thickness of the lining. The exposed edge of the treated portion 36 of the lining will not only be reduced in actual thickness, presumably because of the adhesive qualities of the material which has 30 been employed, but also present an edge adjacent to the French binding which is no longer fuzzy but is substantially regular and straight. Consequently, for this reason alone, it will be much less conspicuous. If desired, the thickness 35 of the lining margin may be reduced by skinning before the ink is applied. Furthermore, the visibility of the edge is reduced because of the coloration at 38 which blends with or matches the coloring of the French binding 18 or of the upper leather, if no French binding is employed. When the trimming is done, a cleaner cut may 40 be made because of the denser and stiffer condition of the leather. The invention also finds utility in the treatment of areas surrounding eyelet holes or other perforations, cut-outs and the

like, and may be applied to the upper stock around such openings.

Having described my invention, what I claim as new and desire to secure by Letters Patent of the United States is:

1. A shoe construction having an upper and a lighter colored lining assembled with the upper so that the raw edge of the lining is exposed beside the upper at an opening in the shoe and so that one surface of the lining is exposed within the shoe, part only of the thickness of the exposed raw edge of the lining having a coloration darker than that of the exposed surface of the lining and similar to that of the adjacent upper, the apparent thickness of the lining being thereby minimized and the exposed surface of the lining being unaffected by said coloration.

15 2. A shoe upper, the exposed edge of which is finished, and a leather lining for said upper, said lining having its exposed grain surface of a color contrasting with that of the finished edge, said lining having its concealed margin adjacent to the finished edge treated with an ink of a color simulating that of said edge, and which has only 20 partly penetrated the lining and hence has colored 25 part of the raw edge of the lining adjacent to the finished edge of the upper, thereby minimizing its apparent thickness.

3. The method of making a shoe upper comprising a light-colored leather shoe lining having its grain surface exposed in the finished shoe which consists in applying directly to the flesh surface of said lining an ink of a color contrasting with that of the lining, said ink being of a quality and in a quantity to penetrate only part of the 35 thickness of the lining and without discoloring the grain surface of the lining, said application being along a band including the line corresponding to the edge of the upper leather, combining said lining with the upper leather by a seam 40 near the coated band with the lining extending beyond the upper leather, and trimming said lining within the coated band.

DOMINICK LA VALLE.
